CLAIM

The ornamental design for a computer housing edge, as shown and described.

DESCRIPTION

FIG. 1 is a perspective view of a computer housing edge in accordance with the new design;

FIG. 2 is a back view of the computer housing edge of FIG. 1;

FIG. 3 is a left side view of the computer housing edge of FIG. 1;

FIG. 4 is right side view of the computer housing edge of FIG. 1;

FIG. 5 is a top plan view of the computer housing edge of FIG. 1;

FIG. 6 is a bottom plan view of the computer housing edge of FIG. 1; and,

FIG. 7 is another top plan view of the computer housing edge of FIG. 1, showing the associated computer in an open configuration.

The broken lines in the drawings showing the remainder of the computer, including the small broken lines depicting vents, speakers, and laptop key ridge features, are directed to environment and are for illustrative purposes only. Accordingly, the broken lines form no part of the claimed design.

1 Claim, 5 Drawing Sheets
